UNITED STATES PATENT OFFICE

HENRY H. YERK AND WILLIAM J. BAUMBERGER, OF DAVENPORT, IOWA, ASSIGNEES
TO MICRO MACHINE COMPANY, OF BETTENDORF, IOWA, A CORPORATION OF IOWA

GRINDING MACHINE

Application filed August 7, 1924. Serial No. 730,626.

This invention relates to grinding machines, and more particularly to internal grinders in which a grinding wheel is mounted on a spindle and caused to revolve bodily about a fixed axis eccentric to its own and also to rotate upon its own axis while a suitable feed mechanism causes a relative movement longitudinally between the grinding wheel and the work.

10 The present invention has for an object the provision of driving means for causing both of the rotative movements of the spindle, in a simple and efficient manner, and for so driving the spindle that it will have a uniform, continuous, movement relative to the work with substantially no vibration in order that accurate grinding may be accomplished and also that the surfaces ground may be smooth and have a superior finish.

20 A further object of the invention is to provide a driving means for causing the rotation of the spindle about its own axis, which driving means will have a substantially uniform bodily movement corresponding to that of the spindle, so that back lash and other irregular movements of the spindle are substantially eliminated, thus permitting the grinding wheel to travel with a uniform motion relative to the work and produce an excellent, ground surface.

Another object of the invention is to provide a mechanism for changing the rate of orbital movement of the grinding wheel spindle in relatively small increments or with intermerging gradations of speed so that relatively small changes of speed can be obtained to secure the best grinding of cylinders of various diameters or to secure grinding of high quality when using wheels of different grain size, thus making the machine of quite general application. Also, it is an object of the invention to have the feeding mechanism so related to the change speed mechanism for the orbital movement of the spindle, that when the speed of the latter is increased or decreased the feeding speed will be correspondingly increased or decreased.

25 A further object of the invention is to provide a common driving means deriving power from a single source for causing the move-

ments of the grinding wheel spindle and for causing the longitudinal feed of the work, such driving means being efficiently arranged to cause such movements with substantially no vibration and such means being easy to maintain and of a simple, efficient, and durable construction.

With the above and other objects in view the invention may be said to comprise the machine as illustrated in the accompanying drawings, hereinafter described and particularly set forth in the appended claims or such variations and modifications thereof as will be obvious to those skilled in the art to which the invention appertains. It is therefore to be understood that while the following description and accompanying drawings set forth in detail certain means embodying the invention, the disclosed means constitutes but one of the various mechanical forms in which the principle of the invention may be employed.

Reference should be had to the accompanying drawings forming a part of this specification in which:

Figure 1 is a side elevation of a grinding machine embodying the invention.

Figure 2 is a side elevation of the machine from the side opposite that shown in Figure 1.

Figure 3 is an end elevation of the machine showing the spindle driving mechanism.

Figure 4 is a horizontal section taken beneath the bed and showing the driving connections from the main drive shaft.

Figure 5 is an end view of the machine with the spindle driving mechanism omitted.

Figure 6 is a vertical longitudinal section through the head.

Figure 7 is a fragmentary section on line 7-7, Figure 1, showing the gearing for driving the feeding mechanism.

Figure 8 is a vertical section on line 8-8, Figure 7.

Referring to the accompanying drawing, the machine consists of a supporting base A which has at the top thereof a bed B upon which the spindle carrying head C is rigidly secured at one end. A work holder F is

mounted upon the power driven table G for movement toward and from the spindle carrying head. The specific structure of the work holder does not concern the present invention, it being sufficient for the present disclosure that this work holder is adapted to be adjusted to rigidly support the cylinder to be ground in alinement with the axis about which the spindle is bodily rotated. The work holder being mounted on the table G is moved longitudinally of the machine when the table G is moved by the usual rack and pinion (not shown). The pinion is driven in the desired direction by suitable reversing gears in the casing E. The automatic reversal of the table is controlled by adjustable stops 1 carried by a longitudinally extending bar 2 which is fixed to the table, the stop 1 engaging a control lever 3 projecting from the gear box 4. In addition to the power drive, the table may be operated by the hand wheel 4a as appears more fully hereinafter.

Referring particularly to Figure 6 of the drawing, the head (C) is provided with spaced bearing portions 5 in which the rotating spindle carrier 6 is journaled. The carrier 6 has an eccentric bore which has conical outwardly flaring end portions and which receives the spindle supporting member 7 which has an integral conical head 8 at its inner end and carries a conical sleeve 9 at its opposite end, the conical sleeve 9 being held in place by a nut 10 on the end of the member 7, the nut 10 being adjustable to engage the conical head 8 and the conical sleeve 9 in the flaring ends of the bore to prevent any endwise play between the supporting member 7 and the carrier 6.

The tool spindle 11 is journaled eccentrically in the inner sleeve support 7 and projects beyond the inner end of the head toward the work support and carries a suitable tool such as a grinding wheel 11a. The outer end of the spindle projects beyond the end of the frame and has a pulley 12 fixed thereto over which the belt which drives the spindle runs. The inner end of the spindle supporting sleeve 7 has a worm gear 13 fixed thereto which meshes with a worm 14 on a shaft 15 which may be operated manually by conventional means (not shown) to turn the sleeve 7 in the carrier 6. Since the sleeve 7 is eccentrically mounted in the carrier 6 and the spindle 11 is eccentrically mounted in the sleeve 7, the spindle may be adjusted with respect to the axis of the carrier 6 by rotating the sleeve 7 with respect to the carrier 6 by means of the worm 14. The spindle carrier 6 has two external gears 16 and 17 fixed thereto by which it may be rotated by power by means later described, or by hand by turning the handle 117, respectively, to revolve the spindle bodily during the operation of the machine. A suitable automatic feed device for adjusting the axis of the

spindle relative to that of the spindle carrier 6 is preferably incorporated on this machine to vary the depth of cut of the grinding wheel while the machine is running. Such an automatic feed device is described in the application of H. M. Jerome, Serial No. 483,195, filed July 8, 1921.

The present invention relates particularly to the driving mechanism for the spindle, spindle carrier and feed mechanism above referred to and this driving mechanism will now be described. Mounted centrally upon the base of the machine at the end opposite that on which the head C is located is an electric motor 18 which has a shaft 19 which extends longitudinally of the base. Adjacent the motor there is a suitable clutch 20 by which the shaft 19 may be connected to or disconnected from a coaxial shaft 21, the clutch 20 being controlled by a shifter 22 which is operated by means of a suitable hand lever 23. The shaft 21 is journaled adjacent its ends in fixed bearing standards 24 and 25, and from this shaft the spindle carrier and feed mechanisms are driven, as will be hereinafter described.

The spindle is driven through mechanism carried at the end of the frame which is directly connected to the shaft 21. Upon the end of the base there is a bracket frame D on which is mounted a horizontally slidable frame 26, which latter frame carries rollers 27 intermediate its ends and upper rollers 29 which engage, respectively, horizontal tracks 28, 30 on the member D. The frame 26 is held in place from movement longitudinally of the machine by means of inner and outer rollers 31 and 32, respectively, carried by a bracket secured to the base of the machine and by similar rollers 34, 35 carried by a bracket on the frame D. The rollers 31 and 34 engage the outer face of the frame 26 and the rollers 32 and 35 engage the inner face thereof and thus hold the frame rigidly against movement longitudinally of the machine while permitting it to freely move in a plane transverse to the machine.

Suspended from the spindle 11, immediately outside the horizontally movable frame 26, is a connecting arm 37 which is hung from the spindle 11 by a ball bearing 38 as shown in Figure 6. The arm 37 hangs vertically and is maintained at all times in vertical position by means of vertically disposed guides 39 and 40 adjacent the top and bottom of the frame 26 which are engaged by rollers 41 and 42, respectively, carried by the arm 37 adjacent the top and bottom thereof. Additional guides 43 preferably channel shaped, may be provided on the frame 26 to engage with rollers 43a on the arm 37 intermediate the upper and lower ends thereof.

In order to counterbalance the weight of the frames 26 and 37 and the parts carried thereby, a counterweight 125 may be pro-

vided. As will be readily seen by reference to Figs. 1 and 4, the counterweight 125 may act through a shaft 126 on the lower portion 127 of the frame 26. The shaft 126 is shown as extending through the cross member 128 to form a ball pivot joint 129. It will be seen that by this means the spindle 11 may be substantially relieved of the weight of the frame 26 and the arm 37 and parts carried thereby.

When the spindle is adjusted as by turning housing 7 relative to carrier 6 so that said spindle has a bodily movement eccentric to its own axis due to the rotation of carrier 6, the arm 37 follows this bodily movement, the arm 37 being guided to move vertically and the frame 26 being guided to move horizontally so that all parts of the arm 37 move continuously and uniformly with the same bodily revolving movement that the spindle has. As the spindle is adjusted to be more or less eccentric to the axis of the main cylinder, its bodily movement and the bodily movement of the arm 37 are, of course, increased or decreased. As shown in Figure 6, the spindle is adjusted to have substantially its maximum eccentric movement but it, of course, may be adjusted by turning the spindle housing 7 so that it has very slight eccentric movement or none at all—that is so that its axis is in alignment with the axis of the main cylinder.

The arm 37 has a bearing portion 44 adjacent its lower end in which is journaled a horizontal stub shaft 45 which carries a relatively large belt pulley 46 outside the arm 37 and projects inwardly through the frame 26 which is cut out to accommodate the spindle 11 and shaft 45. A belt 47 runs over the small spindle pulley 12 and large drive pulley 46 and the arm 37 carries an adjustable belt tightener 48 by means of which the belt may be held at the desired tension. The shaft 45 is so disposed with respect to the axis of the shaft 21 that its bodily movement with respect to the axis thereof corresponds substantially to the bodily movement of spindle 11 with respect to the axis of its carrier 6. The inner end of the shaft 45 is connected to the shaft 21 by means of telescopic shaft sections 49 and 50 connected to the shafts 21 and 45, respectively, by universal joints 51 and 52.

It will thus be seen that the outer support 44 for the spindle drive has a bodily movement corresponding to the bodily movement of the spindle, and that such movement is uniform and continuous in one direction, so that the tension of the belt 47 is always uniform and no vibration is transmitted to the spindle, such as caused by the irregular swing movement of the rocker arms now commonly used which move in arcs different from that of the spindle and thus cause back lash and irregular movements of the belt.

Preferably one of each pair of rolls for guiding the frame 26 and the arm 37 is mounted on an eccentric pin, as is well understood in

the art, so that a relatively accurate fit may be made between the rolls and the surfaces to be engaged thereby.

In order to obtain the best grinding on cylinders of various diameters or with grinding wheels of different grain size, it is necessary to provide means for varying the rates of bodily movement of the spindle and the longitudinal movement of the work with respect to the spindle.

For example, it is well known that with a fine grain grinding wheel the bodily movement revolution or rotation of the grinding wheel spindle about an axis other than its own must be slower in order to prevent the wheel from glazing and to obtain good surfaces, and the speed may be faster when a grinding wheel of larger grain size is used. Also, it has been found that the speed of bodily movement of the grinding wheel should be decreased when grinding a cylinder of larger diameter.

It is therefore essential, to obtain the best grinding, that provision should be made for making relatively small changes of speed of the orbital rotation of the spindle over a substantial range, so that on the same grinding machine the proper speeds may be obtained for grinding cylinders of various diameters and for grinding with wheels of small grain size and large grain size. The changes of speed desirable for most efficient operation may amount to several revolutions per minute or they may be as small as one revolution per minute, depending upon the variations in the work or the grinding wheel. Means is therefore provided for varying the orbital speed in small increments or with intermerging gradations in speed over a relatively wide range of speeds.

In addition to the necessity for making provision for the relatively small changes of speed of the bodily rotation of the spindle, we have found that it is very desirable to vary the speed of the work with respect to the spindle and this should bear a relation to the rate of bodily movement of the spindle, that is, when one is increased or decreased the other should correspondingly be increased or decreased.

It is, therefore, another object of the present invention to have the grinding wheel spindle and work table so driven that their speeds may be simultaneously and automatically varied in small increments or with intermerging gradations to obtain the speeds most suitable for a cylinder of any diameter within the capacity of the machine or suitable for grinding wheels of any desired grain size, so that the proper speed for producing the best ground surfaces on any character of work may be obtained.

A further advantage to be obtained by having suitable change speed mechanism for causing relatively small changes of speed

over a substantial range is that it is very desirable to have the orbital movement of the grinding wheel spindle a little slower when the grinding is done wet than when the 5 grinding is done dry. Thus a grinding machine so equipped with a change speed mechanism is adapted to be used either as a dry or wet grinder and the correct speed for producing the best grinding can be obtained.

10 While it is possible to incorporate in our machine separate means for changing the speed of the orbital movement of the spindle and travel of the work, this leaves the correct adjustment of such speeds to the operator 15 and we have deemed it more desirable to have the travel of the work and the rate of orbital movement of the spindle so related that when the speed of one is increased or decreased the speed of the other is automatically increased or decreased in proper proportion.

In addition to having the work carrying table driven from the variable speed mechanism for driving the headstock so that the 20 rate of longitudinal travel of the table increases or decreases as the number of revolutions per minute of the headstock increases or decreases, it is very desirable to provide for independently adjusting the amount of 25 table travel for each revolution of the headstock so that the grinding machine will be adapted to grind various sizes and kinds of work with various grinding wheels. For example, the table can be made to move any 30 desired number, such as 35 or 40 thousandths of an inch longitudinally, for each revolution of the headstock, this being, of course, independent of the number of revolutions that are made per minute. This is in order 35 that, as the depth of a cut is increased or decreased by varying the eccentricity of the spindle in the spindle carrier, the amount of longitudinal travel of the wheel relative to the work can be increased or decreased to 40 vary the ratio between the feed and spindle movements so that the best results in grinding 45 may be obtained.

The change speed device for varying the orbital movement of the spindle and the longitudinal movement of the table will now be 50 described. It is mounted upon the rear side of the base below the head and consists of two reversely arranged cone pulleys 53 and 54 of the same size journaled in fixed bearings one above the other with their axes and surfaces parallel and their peripheries slightly spaced.

The upper pulley 53 of these cone pulleys is driven from the main drive shaft 21 in the 55 following manner. It has at one end a gear 55 which meshes with a gear 56 on a parallel stub shaft 57 which carries a belt pulley 58 over which runs a belt 59 which extends over a pulley 60 on the shaft 21. The lower cone 60 pulley 54 is driven from the upper pulley by

means of a belt 61 which encircles the lower cone pulley and is adjustable longitudinally of the pulleys to give the desired speed ratio between the two. As will be explained, the spindle carrying sleeve and the work feed 70 are both driven from the lower pulley 54 so that as the speed of one is varied the speed of the other is proportionately varied.

For shifting the belt 61 there is a yoke 62 straddling the belt and slideable along an inclined guide rod 63 parallel to the continuous peripheral portions of the conical surfaces of the cones. The yoke 62 is connected to the ends of a cable 64 which runs over a pulley or sheave 65 adjacent one end of the cone pulleys and has its upper and lower runs parallel to the guide rod 63. Adjacent the forward end of the base, the cable 64 is guided transversely through the base over guide pulleys 66 and 67 on the rear side of the base adjacent the cone pulleys there over, pulleys 68 adjacent the bottom of the base and pulleys 69 adjacent the top thereof beneath the head, and over horizontally disposed and horizontally aligned pulleys 70 at the front of the base. The portion of the cable between the pulleys 70 is disposed horizontally and outside of the casing at the front of the machine and has attached thereto a handle 71 by which the cable may be shifted to shift the yoke 62 and belt 61 longitudinally of the cone pulleys. The handle 71 is provided with a pointer 72 and extending along the cable and above the same is a suitably graduated scale 73 along which the pointer moves. The scale 73 provides means for indicating very accurately the speeds for which the spindle rotating and feed mechanism are set so that the operator may very quickly set the change speed mechanism to the proper point for the size of the work and the kind of grinding wheel used.

For operating the spindle carrying sleeve the shaft carrying the lower pulley 54 has fixed thereto at its forward end a belt pulley 74 from which runs a belt 75 which passes over a pulley 76 on a countershaft 77 beneath the head, the shaft 77 having a spur gear 78 meshing with the spur gear 16 on the spindle carrying sleeve 6.

For operating the table G the lower cone pulley 54 has at its opposite end a pulley 79 over which runs a belt 80 which passes over a pulley 81 on a counter shaft 82 journaled in the standards 24 and 25 directly beneath the drive shaft 21. The countershaft 82 carries a second belt pulley 83 which drives the belt 84 which extends into the pulley housing 84a at one end of the feed gear box 4 and engages the pulley 85 to operate the gearing within the gear box 4 through which the pinion and rack or other work shifting device is operated.

Within the gear box 4 there is a reversing gear indicated generally at 85a of the usual bevel gear and intermediate clutch type which drives in either direction a stub

shaft 86 which extends into the casing beneath the bed and has upon its inner end a bevel gear 87 which meshes with a bevel gear 88 on a countershaft 89 which carries a spur gear 90 meshing with a larger gear 91 on a counter-shaft 92 which has fixed thereto a series of gears 93 which are of gradually decreasing size toward the forward end of the shaft. These gears 93 mesh with gears 94 loosely mounted on a parallel shaft 95, the gears 94 varying in size in reverse order as is common in speed change gearing. The shaft 95 is hollow and slideable therein is a key rod 96 carrying a key 97 which extends through a slot in the shaft 95 and is adapted to engage with any one of the gears 94 to key it to the shaft. Between each of the gears 94 there is a neutral space provided by washers 98 in which the key may be positioned so that the drive of the shaft 95 may be discontinued by shifting the key in either direction out of engagement with any one of the gears 94.

The shaft 95 being thus driven by anyone of the gears 94 serves to drive the work table G in the following manner. It has fixed thereto at its rear end a pinion 99 which meshes with a pinion 100 carried by the horizontal shaft 101 which drives through coupling 102 the worm gear 103. The worm gear 104 carried on the vertical shaft 105 is driven on the worm gear 103 and the shaft 105 projects up to the bed of the machine and carries a pinion 105a which engages the rack (not shown) for moving the work table G backward and forward.

The rod 96 projects forwardly beyond the end of the hollow shaft 95 and this projecting end has a rack portion 106 formed by closely spaced, parallel, circumferential grooves, the rack portion 106 being engaged by a pinion 107 by means of which the rod 96 may be shifted longitudinally. The pinion 107 is fixed to a sleeve 108 loose on the transverse hand wheel shaft 109 and this sleeve 45 has attached thereto outside the casing a handle 110 by means of which it may be turned to shift the key rod 96 to engage any desired gear 94 to obtain the desired rate of feed of the table G or to disconnect the shaft 50 95 to stop the movement of the table. It will be noted that by shifting the rod 96 with the key 97 in either direction from the gears 94 the key will engage a neutral washer 98 which will stop the movement of the table G. 55 The operation that has just been described relates to the means for driving the table G automatically at any desired speed. In order, however, to provide for manual operation of the table so that it can be set at any 60 desired point, the hand wheel shaft 109, which may be operated in either direction by the hand wheel 4a mounted thereon, carries a bevel gear 111 fixed to its inner end and this gear meshes with a bevel gear 112 on a counter-shaft 113 extending parallel to the

shaft 95, the shaft 113 having a pinion 114 meshing with a pinion 115 fixed to the shaft 95.

It will thus be seen that the table G may be set to any desired position by the hand wheel 4a and that the handle 110 may be independently adjusted so that the amount of table travel for each revolution of the head stock can be selected so that it will be suitable for the depth of cut or for the character of grinding wheel used, as previously explained.

This mechanism, therefore, provides means for changing the ratio of speeds of the table travel and spindle movements to suit the grinding machine to obtain the best results with various conditions. Such change of the ratio of speed is of course independent of the relationship between the table travel and the bodily movement of the spindle, wherein the latter increases or decreases in speed when the former increases or decreases in speed. This latter relationship arises from the arrangement whereby the driving mechanism for causing the bodily movement of the spindle and the driving mechanism for causing longitudinal movement of the table are driven from the same cone pulley, and the rate of rotation of the cone pulley may be varied within relatively small amounts over a relatively wide range by means of the belt shifting mechanism associated with the cone pulley mechanism as previously explained.

It will thus be seen that we have developed a grinding machine of general application to grind cylinders of various sizes and with grinding wheels of various grain size and various diameters and for grinding such cylinders either dry or wet, as desired. By having these factors which so vitally affect the grinding variable and within the control of the operator it is possible to produce practically any desired finish on work of widely differing properties.

It will be noted that our grinding machine is adapted to grind cylinders either by the dry or the wet process as desired. For wet grinding a suitable hollow spindle carrying a liquid conducting tube and a suitable baffle plate such as shown in the application of William J. Baumberger, Serial No. 602,068, filed November 20, 1922, may be used. As indicated in Figure 6 but not shown in the other figures of the drawing a hose 120 may be provided to supply liquid to the liquid conducting tube 121 carried by the spindle 11. A bracket 122 supported on the arm 37 engages the rear end of the spindle and together with the nut 123 contains the liquid and directs it into the tube 121 which passes through the spindle as in the copending application above referred to.

It is to be understood that while we have indicated how our grinding machine is adapted for introducing the liquid for wet grind-

ing as one way, that we are by no means confined to using this particular manner of supplying the liquid for wet grinding. Our machine disclosed herein may be equally well used to obtain a superior grade of dry grinding or to obtain the still better finishes which it is known can be produced by wet grinding.

In the operation of the machine a cylinder to be ground is clamped to the work support F carried by the table G. It is set manually so that the axis of the cylinder is in alignment with the axis of the orbital movement of the spindle and the table G is operated by the handle 4a so that the cylinder is in proper position longitudinally of the spindle for feeding it backward and forward. The operating handle 71 of the speed regulator 50 is adjustable on the scale 73 to bring the pointer 72 to the position to cause the proper number of revolutions per minute of the spindle for the size and character of the work being operated upon and the character of grinding wheel being used. The handle 110 is set to cause the table to travel the correct amount longitudinally for each revolution of the head stock, as is determined by the depth of cut to be made, the character of grinding wheel to be used and the character of the work.

Furthermore it is to be understood that the particular forms of apparatus shown and described, and the particular procedure set forth, are presented for purposes of explanation and illustration and that various modifications of said apparatus and procedure can be made without departing from our invention as defined in the appended claims.

What we claim is:

1. In a grinding machine, a grinding wheel spindle, means for revolving said spindle bodily about an axis eccentric to its own, means for rotating said spindle about its own axis, a supporting member carried by the spindle and being free to move in response to the bodily movement of the spindle and a rotatable driven element carried by the supporting member for causing the rotation of the spindle on its own axis and means for driving said element and for driving the spindle therefrom.

2. In a machine of the character described, a tool spindle, means for moving said spindle bodily about a fixed axis and means for driving said spindle about its own axis, said means comprising a driving pulley on the spindle, a pulley on a driving shaft, a belt passing over said pulleys, and means carried by the spindle for imparting to said driving shaft pulley a bodily movement corresponding to that of the bodily movement of said spindle pulley.

3. In a grinding machine, a grinding wheel spindle, a rotatable support for the spindle having an axis of rotation parallel to the axis of the spindle, means for rotating said

spindle support to impart a bodily revolving movement to the spindle, supporting means carried by the spindle, guiding means mounted on the machine and so arranged as to permit said supporting means to freely move in the same path as that of the bodily movement of the spindle but holding said supporting means against rotation with the spindle, a drive shaft and means for driving the spindle from said drive shaft through said supporting means.

4. In a grinding machine, a grinding wheel spindle, a rotatable sleeve for the spindle, having an axis of rotation parallel to the axis of the spindle, means for rotating said sleeve to impart a bodily revolving movement to the spindle, supporting means carried by the spindle, guiding means on the machine so arranged as to permit said supporting means to freely move in the same path as that of the bodily movement of the spindle, a drive shaft section carried by said supporting means, means connecting said section with said spindle for revolving the spindle about its own axis, a driving shaft journaled in said machine, and connecting shaft sections telescopically connected together and connected by universal joints with said drive shaft section and driving shaft.

5. The invention specified in claim 4 in which said supporting means is counterweighted.

6. In a machine of the character described, a frame having a head, a sleeve rotatable therein, a spindle journaled eccentrically in the sleeve, means for rotating the sleeve, a supporting member suspended from the spindle, said supporting member having a bearing in which the spindle is journaled, a guide member slidably mounted on the head and having guides for said supporting member which permit a movement of the supporting member relative to said guide member in a direction at an angle to the direction of movement of the guide member with respect to the frame, and driving means for the spindle mounted on said supporting member.

7. In a grinding machine, a grinding wheel spindle, means for revolving said spindle bodily about an axis eccentric to its own, a supporting arm carried by the spindle, a laterally movable frame mounted in guides on said machine for horizontal movement, guides on said frame for permitting vertical movement of said arm, a driving shaft journaled in said arm and means connecting said drive shaft with said spindle for rotating said spindle about its axis, said drive shaft having a universal connection with a driving shaft journaled in the frame of the machine.

8. The invention specified in claim 7 in which said supporting means is counterweighted.

9. In a grinding machine, a grinding wheel spindle, means for revolving the spindle

bodily about an axis parallel to its own, said spindle being mounted to rotate about its own axis, means comprising a supporting member operating in guides carried by the machine and receiving a bodily motion corresponding to the bodily motion of the spindle about the parallel axis, a driving shaft journaled in the base of the machine, shaft sections carried by said supporting member and connected with said driving shaft so that the outer end of said section can move with said supporting member and a belt means connecting said outer shaft section with said spindle to drive the same about its own axis.

10. In a grinding machine, a grinding wheel spindle, means for simultaneously rotating the spindle about its own axis and about an axis parallel thereto, supporting means suspended from the spindle and partaking of the bodily movement thereof and movably mounted therein, a guide frame, said frame being laterally movable in guides on the grinding machine and having means to guide 20 said supporting means, whereby said supporting means has uniform, continuous bodily movement corresponding to that of the spindle, and driving means carried by said supporting means for causing rotation of the 25 spindle about its own axis.

11. In a grinding machine, a base, a grinding wheel spindle supported on the base, a laterally movable frame supported on guides mounted on said base, a supporting member 35 suspended from the spindle, mounted in the frame and guided for vertical movement in the said laterally movable frame, means for rotating the spindle bodily about an axis parallel to its own, driving means for rotating the spindle about its own axis, said latter means being carried by the supporting member.

12. In a machine of the character described, a tool spindle having a pulley 45 thereon, means for rotating said spindle bodily about an axis eccentric to its own, a second pulley larger than the spindle pulley and a rigid supporting member upon which the second pulley is mounted, said supporting member being suspended from the spindle, a belt passing over said pulleys, a drive shaft on a fixed support, and a driving connection from said drive shaft to said second pulley.

13. In a machine of the character described, a tool spindle, means for rotating said spindle bodily about an axis eccentric to its own, a rigid supporting arm carried by the spindle, a driving element carried by said 60 arm for rotating the spindle about its own axis, a fixed drive shaft, and a driving connection from said drive shaft to said driving element.

14. In a machine of the character described, a tool spindle, means for rotating said

spindle bodily about an axis eccentric to its own, a rigid arm carried by the spindle, pulleys carried by the spindle and arm, respectively, a belt connecting the pulleys, guides for permitting said arm to partake of the same bodily movement as the spindle, means on said arm for driving the pulleys, and means carried by the arm for keeping the belt passing over said pulleys tight, whereby said spindle is caused to have a continuous, uniform movement substantially free from vibration.

15. In a machine of the character described, a tool spindle, means for rotating said spindle bodily about an axis eccentric to its own, a pulley mounted on the spindle, a second pulley, a rigid arm maintaining said spindle and pulley in definite relation, means for guiding said second pulley in a circular path corresponding to the path of movement of the spindle pulley, and means for driving said second pulley comprising a rotatable drive shaft fixed against bodily movement, and a shaft section connected by universal connections with said second pulley and said drive shaft.

16. In a grinding machine, a grinding wheel spindle, means for rotating said spindle bodily about an axis eccentric to its own and means for rotating it about its own axis, supporting means suspended from the spindle movably mounted in a guide frame and partaking of the bodily movement of said spindle, said guide frame being laterally movable in guides on the grinding machine and having means to guide said supporting means, said frame and supporting means being movable in substantially parallel vertical planes transversely of the spindle and held against movement longitudinally of the spindle, driving means carried by the supporting means for causing rotation of the spindle about its own axis, said driving means being actuated by telescopic shaft sections connected to a main driving shaft.

17. In a grinding machine, a grinding wheel spindle, means for rotating said spindle bodily about an axis eccentric to its own and means for rotating the spindle about its own axis, a rigid, guided supporting arm carried by said spindle for bodily movement therewith, a shaft carried by said arm to drive said spindle about its own axis, driving connections between said shaft and said spindle, a fixed drive shaft and a pair of telescopic shaft sections connected by universal connections with said fixed drive shaft and said shaft carried by the arm.

18. In a grinding machine, a grinding wheel spindle, means for revolving said spindle bodily about an axis eccentric to its own, means for rotating said spindle about its own axis, said revolving and rotating means deriving power from a common driving shaft, said spindle rotating means being

carried by the spindle so that it has the same bodily movement as the spindle.

19. In an internal grinding machine for grinding cylindrical bores, in combination, a tool spindle, means for rotating said spindle orbitally about an axis eccentric to its own, a power transmission member disposed in unaligned relation to and remote from said tool spindle, and means for driving said spindle about its own axis from said member, including a rotary member eccentric to the tool spindle and moving therewith in an exactly corresponding orbit.

20. In an internal grinding machine for grinding cylindrical bores, in combination, a grinding wheel spindle having an orbital movement about an axis eccentric to its own, the radius of said orbital movement being changeable, a power transmission member spaced from said spindle in an unaligned relation to and remote from said spindle, a gyratory driving connection from said source of power to said spindle to cause rotation of said spindle about its own axis, said driving connection having a continuous and uniform orbital movement exactly corresponding to the orbital movement of the spindle.

In testimony whereof, we hereunto affix
30 our signatures.

HENRY H. YERK.

WILLIAM J. BAUMBERGER.
